[57] CLAIM

The ornamental design for a equipment cabinet front panel, as shown and described.

DESCRIPTION

FIG. 1 is a front elevation of the equipment cabinet front panel showing my new design;

FIG. 2 is a left side elevation thereof, the right side elevation being a mirror image;

FIG. 3 is a top plan view thereof;

FIG. 4 is a bottom plan view thereof;

FIG. 5 is a front elevation of a second embodiment thereof wherein the only difference is in the extended grooves shown along the top portion; and,

FIG. 6 is a left side elevation thereof, the right side elevation being a mirror image;

The undisclosed rear view is unornamented.

FIG. 1

FIG. 2

FIG. 3

FIG. 4

FIG. 5

FIG. 6
